UNITED STATES PATENT OFFICE.

NATHAN R. MAYOZA AND ALFRED H. MURRAY, OF MEMPHIS, TENNESSEE.

DESIGN FOR A FACEPLATE FOR AN AUTOMOBILE SIGNAL.

Application filed September 14, 1925. Serial No. 14,786. Term of patent 14 years.

To all whom it may concern:

Be it known that we, NATHAN R. MAYOZA and ALFRED H. MURRAY, both citizens of the United States, residing at Memphis, in the county of Shelby and State of Tennessee, have invented a new, original, and ornamental Design for Faceplate for Automobile Signals, of which the following is a specification, reference being had to the accompanying drawing, forming part thereof.

The figure is a front elevation of the faceplate for an automobile signal.

We claim:

The ornamental design for a faceplate for an automobile signal substantially, as shown.

In testimony whereof we have hereunto set our names.

ALFRED H. MURRAY.
NATHAN R. MAYOZA.
